FOLDABLE BOX

Walter H. Fairchild, Baltimore, Md., assignor to
 The Baltimore Paper Box Company, Baltimore,
 Md., a corporation of Maryland

Application January 27, 1934, Serial No. 708,644

5 Claims. (Cl. 229—41)

The invention relates to improvements in shallow boxes, usually constructed from heavy cardboard, straw-board, fiber-board or the like, and having such fold lines as to permit the four walls 5 of the box to downwardly fold to horizontal positions, economizing in space for shipment, storage, etc. While boxes of this character are very desirable, difficulty is encountered in keeping their walls in vertical position during box packing, there being a great tendency of the diagonally creased walls to bulge and fold downwardly and outwardly causing a corresponding inward and downward movement of the other walls. It is to provide a new and improved box of this 10 character, in which this difficulty is effectively overcome, that I have produced the present invention.

In carrying out the above end, a further object has been the production of a commercially 20 practicable structure free from such complication as to interfere with cheap and rapid manufacture, so inexpensive that the purchase price will not be prohibitive, and so easily set up for use as to entail no trouble or loss of time.

25 With the foregoing in view, the invention resides in the novel subject matter hereinafter described and claimed, description being accomplished by reference to the accompanying drawings.

30 Fig. 1 is a perspective view showing one form of the box in the flat folded condition in which it reaches the user.

Fig. 2 is a perspective view showing the box 35 partially opened up for use.

Fig. 3 is a perspective view of one end of the box showing the manner in which the walls are held vertical.

Fig. 4 is a detail vertical sectional view on line 4—4 of Fig. 3.

40 Fig. 5 is a perspective view showing one of the struts employed to prevent return of the box to collapsed condition after it has been opened for use.

Fig. 6 is a view similar to Fig. 1, but showing 45 a different form of construction.

Fig. 7 is a perspective view showing the box of Fig. 6 partially opened for use.

Fig. 8 is a perspective view of one end of the box showing the manner in which it is held 50 against collapse after opening for use.

Fig. 9 is a perspective view similar to Figs. 1 and 6 but showing a third form of construction.

Fig. 10 is a perspective view showing the box 55 of Fig. 9 partially opened up for use.

Fig. 11 is a perspective view of one end of the box showing the manner in which it is held against return to collapsed condition.

Only the lower section of the box has been disclosed and it will be understood that the usual telescopic cover may be of similar construction if desired.

For purposes of illustration, corrugated fibre board or "straw board" has been shown, but it is to be understood that any rather stiff material could be used. Moreover, the box may obviously be constructed in various sizes and proportions.

The form of construction shown in Figs. 1 to 5 will first be described. In these views, 12 denotes a rectangular bottom. Foldably connected with the bottom 12 and preferably integral therewith are two parallel walls 13 having extensions 14 foldably connected with their ends, said extensions being preferably integral with said ends. Two additional parallel walls 15 are foldably connected with the bottom 12 and are preferably integral therewith. These walls 15 are permanently secured against the inner sides of the extensions 14, by rivets 16 or in any other desired way, and they are provided with vertical end edges 17 which are inwardly spaced slightly from the inner sides of the walls 13. These edges 17, the portions of the walls 13 opposed thereto, and the contiguous portions of the extensions 14, jointly form four vertical grooves 18 disposed 20 one in each corner of the box.

The walls 13 are creased or otherwise provided with fold lines 19 which permit the four walls 13 and 15 to jointly fold downwardly to the collapsed condition shown in Fig. 1. To prevent 25 return to this condition after the box is opened up for use however, struts 20 are provided to snap into the grooves 18 and to be held in operative

position by said grooves. In the form of construction under consideration, there are two of 30 the struts 20, each strut consisting of a rectangular strip creased and stapled at 21, or otherwise foldably connected with the bottom 12 along the lower edges of the walls 13. Each strut is pro-

vided with vertical end edges 22 to snap into the 35 grooves 18. When the walls 13 and 15 are unfolded from the collapsed condition shown in Fig. 1, the struts 20 which normally lie upon the bottom 12 as seen in said figure, are easily swung up-

wardly as shown in Fig. 2, and the resiliency of 40 the material from which the improved box is constructed, allows the vertical end edges 22 to snap into the grooves 18, as seen in Fig. 3, so that the struts hold the walls 13 and 15 against 45 50 55

return to collapsed condition, said struts then also reinforcing the ends of the box.

In the form of construction shown in Figs. 6 to 8 inclusive, the parts 12^a, 13^a, 14^a, 15^a and 16^a are duplicates of the parts 12, 13, 14, 15 and 16 above described. The only difference between the two forms of construction being in the structure and mounting of the struts. In the form of construction now under consideration (Figs. 6 to 8), the struts are denoted at 20^a, and four of these struts are used, disposed in pairs at the opposite ends of the box. Each pair of struts is formed from a single rectangular strip foldably connected between its ends to the adjacent wall 13^a, the strip being creased and stapled at 21^a in the present disclosure. The vertical end edges 22^a are intended to snap into the grooves 18^a, preventing functioning of the fold lines 19^a, so that the box cannot return to its collapsed condition, after it is once opened up for use.

In Figs. 9 to 11, the parts 12^b, 13^b, 14^b, 15^b and 16^b, correspond to the parts 12, 13, 14, 15 and 16 previously described, and also to the parts 12^a, 13^a, 14^a, 15^a and 16^a. However, whereas the walls 13 and 13^a are shorter than the walls 15 and 15^a, the walls 13^b are longer than the walls 15^b. The walls 13^b are formed with the inclined fold lines 19^b and folding of the box is prevented when it is set up for use, by struts 20^b. These struts are formed from four separate strips creased and stapled at 21^b to the walls 13^b, and they are provided with vertical end edges 22^b to snap into the grooves 18^b.

It will be seen from the foregoing that novel and advantageous provision has been made for carrying out the objects of the invention, and while three practicable forms of construction have been disclosed, it is to be understood that the invention may also be embodied in other forms. The present disclosure is therefore to be considered as illustrative rather than limiting.

I claim:

1. A box comprising a rectangular bottom, a pair of parallel rectangular walls foldably connected with said bottom and having extensions foldably connected with their ends, an additional pair of parallel rectangular walls foldably connected with said bottom and permanently secured against the inner sides of said extensions, the

vertical end edges of said additional walls being inwardly spaced from the first-named walls, whereby said vertical end edges, the portions of the first-named walls opposed thereto, and the contiguous portions of said extensions jointly form four vertical grooves in the corners of the box, said first-named walls having fold lines inclining from the lower ends of said grooves to allow joint downward folding of the four walls, and struts to normally prevent such folding, said struts being engaged with said grooves and held in operative position thereby.

2. A box comprising a rectangular bottom, a pair of parallel rectangular walls foldably connected with said bottom and having extensions foldably connected with their ends, an additional pair of parallel rectangular walls foldably connected with said bottom and permanently secured against the inner sides of said extensions, the vertical end edges of said additional walls being inwardly spaced from the first-named walls, whereby said vertical end edges, the portions of the first-named walls opposed thereto, and the contiguous portions of said extensions jointly form four vertical grooves in the corners of the box, said first-named walls having fold lines inclining from the lower ends of said grooves to allow joint downward folding of the four walls, and struts foldably connected with the box in position to swing across said inclined fold lines and to snap into said grooves to prevent said joint downward folding of said walls.

3. A structure as specified in claim 2; said struts consisting of two flat rectangular strips foldably secured to said bottom along the lower edges of said first-mentioned walls respectively and having vertical end edges to snap into said grooves.

4. A structure as specified in claim 2; said struts consisting of two flat rectangular strips foldably secured between their ends against the inner sides of said first-named walls respectively, said strips having vertical end edges to snap into said grooves.

5. A structure as specified in claim 2; said struts consisting of four flat rectangular strips foldably secured against the end portions of said first-named walls and having vertical end edges to snap into said grooves.

WALTER H. FAIRCHILD.
